UNITED STATES PATENT OFFICE.

THOMAS S. BURNETT, OF SYRACUSE, NEW YORK.

CARRIAGE-TOP.

SPECIFICATION forming part of Letters Patent No. 247,161, dated September 20, 1881.

Application filed May 9, 1881. (No model.)

To all whom it may concern:

Be it known that I, THOMAS S. BURNETT, of Syracuse, in the county of Onondaga, in the State of New York, have invented new and 5 useful Improvements in Carriage-Tops, of which the following, taken in connection with the accompanying drawings, is a full, clear, and exact description.

This invention relates to a novel arrangement of the slat-irons, bows, and braces of a folding carriage-top and the relative positions of the pivotal connections of said slat-irons, whereby said carriage-top is firmly supported, the back quarter or back curtain thereof is relieved of strain, and the ingress to the carriage 15 is rendered more commodious.

The invention also relates to a simple and effective device for supporting the carriage-top when in a folded position.

20 The invention is fully illustrated in the accompanying drawings, wherein Figure 1 is a perspective view of a carriage-seat provided with my improvements. Fig. 2 is an enlarged detail view of the skeleton-frame of the improved carriage-top, and Fig. 3 is an enlarged detached view of the joint of that slat-iron to which the top-prop is attached.

Similar letters of reference indicate corresponding parts.

30 A, B, and C represent three wooden bows of the usual form, supporting, respectively, the rear, front, and center of the carriage-top when erected.

The rear bow, A, is forwardly inclined and 35 has rigidly attached to each of its extremities a so-called "slat-iron," a, which has its lower end pivoted to the rail R, permanently secured to the sides of the carriage or its seat.

The front bow, B, is rearwardly inclined and 40 has its extremities firmly secured to slat-irons c, which cross the slat-iron a, and are pivoted to the rear end of the rails R respectively, at opposite sides of the seat. The slat-iron c is also pivoted to the slat-iron a at their point 45 of crossing by a bolt passing through eyes b b on the respective irons. Intermediately between the aforesaid pivotal connections of the slat-iron c said iron is provided with a knuckle-joint, d, which allows the section below said

joint to fold downward and causes the upper 50 end of the bow B to swing rearward.

The two bows A and B are braced in their distended or erect position by a rod, D, pivoted at its extremities to the upper portion of the said bows.

55 An intermediate knuckle-joint, f, in the rod D, in conjunction with the knuckle-joint d in the slat-iron c, allows the carriage-top to fold rearward.

It will be observed that by the arrangement 60 of the bows and their respective slat-irons, disposed diagonally and crossing each other in the manner described and shown, the carriage-top is thoroughly braced when erected, so as to effectually relieve the back quarter and back curtain 65 of the strain which ordinary carriage-tops subjects them to. Furthermore, my improved carriage-top renders the front of the seat more readily accessible.

Between the slat-irons a and c of the rear 70 and front bows one or more intermediate bows, C, are pivoted, said bow C supporting the central portion of the carriage-top, and having on its extremity an iron, e, pivoted on the bolt which connects the front bow, B, to the rear 75 bow, A, at their point of crossing.

To properly support the carriage-top when opened and folded back I provide the lower section of the slat-iron c with a rigid rearward extension, r, having a laterally-projecting pad 80 or shoulder, s, to receive and support the bow A and intermediate bows C when thrown back, as illustrated by dotted lines in Fig. 2 of the drawings.

Having described my invention, what I claim 85 as new, and desire to secure by Letters Patent, is—

1. The forwardly-inclined rear bow, A, having the slat-iron a pivoted to the forward part of the rail R, and provided intermediately with 90 the eye b, the rearwardly-inclined front bow, B, having the slat-iron c crossing the iron a and pivoted to the rear part of the rail R and to the eye b respectively, and provided between said pivotal connections with the 95 knuckle-joint d, the central bow, C, terminating with an iron, e, pivoted to the irons a and c at or near their point of crossing, and the brace

D, pivoted to the upper portion of the bows A and B respectively, and having intermediately the knuckle-joint f, all as shown and described.

2. In combination with the bows A and B, 5 crossing each other and pivoted together and to the front and rear end of the rail R respectively, as shown, the slat-iron e, provided with the knuckle-joint d and with the rigid rearward extension r, having the laterally-projecting pad or shoulders, substantially as described 10 and shown, for the purpose set forth.

In testimony whereof I have hereunto signed my name and affixed my seal, in the presence of two attesting witnesses, at Syracuse, in the county of Onondaga, in the State of New York, 15 this 30th day of April, 1881.

THOMAS S. BURNETT. [L. S.]
